Application March 20, 1934, Serial No. 716,457

3 Claims. (Cl. 24—178)

The present invention relates to improvements in fasteners or buckles designed for the retention and adjustable anchoring of straps in belts, collars, harnesses and the like.

5 One object of the invention is to provide a structurally simple and ornamental buckle adapted to securely fasten the free end of a strap in one of several positions.

With this and other objects in view, a feature 10 of the invention contemplates the provision of a buckle body having a substantially closed front portion suited for the reception of engraving or marking, and provided with a tongue opening and spring detent. The body is designed for the 15 sliding reception of a free strap end behind the front plate, with holes in the strap registering with the opening in the plate, and is provided at one side with a pintle for anchoring the opposite end of the strap or belt, and serving as the pivot 20 point for a tongue member which, in closed position, projects through the opening in the strap, the opening in the plate engaging with the spring-pressed detent for locking the tongue in closed position. The tongue may be conveniently provided 25 with a closed eye or loop which projects through the front plate and serves for the reception of a locking device such as the bail of a pad-lock or the like.

Still further features of the invention consist 30 in certain novel features of construction, combinations and arrangements of parts hereinafter described and claimed, the advantages of which will be obvious to those skilled in the art from the following description.

35 In the accompanying drawing illustrating the preferred form of the invention, Fig. 1 represents a perspective of a dog collar employing my new and improved buckle; Fig. 2 is a cross-section illustrating the buckle in open position anchored 40 to one end of the collar; Fig. 3 is a somewhat similar view illustrating the buckle in closed position with the free end of the collar retained thereby; and Figs. 4 and 5 are detail sections on the lines 4—4 and 5—5, respectively, of Fig. 2.

45 The present invention as shown in its illustrated embodiment is designed for use with dog collars, where the simplicity of the locking device and the ornamental appearance of the buckle front is particularly desirable. In its application 50 to this form of article, the collar is indicated generally at 10, and is anchored to the buckle at one end through a loop 12, permanently closed by stitching or otherwise, and passing about the pintle rod 14. The buckle comprises a curved body portion 16 formed generally as a stamping,

and having a generally closed front plate 18 and sides 20 terminating in separated tabs 22 to provide a closed passage or housing for the sliding reception of the free collar end 24. The pivot pintle 14 is supported at opposite ends in offset 5 lugs 26, extending from the sides 20, and allowing for the passage of the free end 24 between the front plate of the buckle and the anchored end of the collar, as illustrated in Fig. 1.

Pivotedly connected to the pintle 14 and mounted 10 behind the front plate 18 is a tongue member 30, which upon closing movement passes between the tabs 22 and through an opening or slot 32 formed in the front plate, as indicated in Figs. 1 and 3. In completely closed position 15 an eye 34 formed in the end of the tongue projects through the front plate from behind for the reception of a pad-lock or similar device. The tongue may also be provided with a shoulder 36 which engages with the portion 38 of a detent 20 spring 40 to limit further closing movement of the tongue. In this position the convex curvature 42 of the tongue resists disengagement of the tongue from the opening in the buckle body, and effectually maintains the buckle in closed 25 position for all ordinary uses without the necessity of inserting a pad-lock or similar device therethrough. On the other hand, the buckle may be readily opened by pressure upon the outwardly extending end of the tongue which projects 30 through the front face of the buckle. It will be observed from an inspection of Fig. 3 that the end of the tongue having the eye 34 is disposed at an acute angle to the length of the tongue in such a manner that the tongue when in closed 35 position engages the free end of the collar at the apex of the angle, and pulling upon the free end of the collar does not result in a wedging action tending to disengage the tongue. Furthermore, the lengthwise portion of the tongue lies in the 40 slot formed by the separated tabs 22 without any substantial projection therebeyond.

As is usual in devices of this character, the free end of the collar may be provided with a series of openings 50 designed for engagement 45 by the tongue, and the free end beyond the buckle may be retained by a loop 52 made of material similar to that of the belt.

The illustrated embodiment of the invention indicates clearly the attractive nature of the 50 buckle and the provision of the front plate of the buckle body for the reception of any suitable marking, as by engraving or otherwise.

The detent spring is conveniently retained in closed position by a curled-over flange 54, formed 55

by the extended end of the buckle plate and engaging the inturned ends 56 of the spring to anchor this portion of the spring in fixed relation to the buckle body.

- 5 5. It will be evident to those skilled in the art that the present buckle in its application, for example, to dog collars, actually serves the function of three separate elements of such a collar as previously used, namely, the usual or orthodox
- 10 10. buckle, the separate name plate employed for the reception of the owner's name and license number, and the D-ring for the attachment of a leash. In addition, the retention of the free strap end by the buckle itself dispenses with the
- 15 15. employment of one of the two leather loops commonly necessary. With the present construction the front face of the buckle body provides space for the reception of the owner's name and license number, and the closed end of the tongue projecting therethrough may be employed for the attachment of a leash or the like.
- 20 20.

What is claimed is:

1. A buckle comprising a body portion having a front plate provided with a tongue opening, 25 a tongue pivoted behind the front plate and provided with a free end forming a closed loop designed to enter the tongue opening from the rear and project therebeyond at the front of the plate when the tongue is closed, and spring detent means cooperating with the free end of the tongue for engagement therewith to hold the latter within the opening, the projecting closed loop of the tongue being designed for the reception of a leash or padlock bail to prevent withdrawal of the tongue.
- 30 30.
- 35 35. 2. A buckle suitable for application to dog collars or the like comprising a buckle body enclosing a space corresponding generally in cross-section to that of the collar and designed for

sliding reception of the free end of the collar, the buckle body having a substantially closed front plate with a tongue opening therein with side flanges terminating in inturned and separated tabs, a tongue mounted behind the front plate of the buckle and pivotally connected therewith, the tongue having a free end portion terminating in a closed loop disposed at an angle with respect to the length of the tongue and designed to project through the opening in the front plate when the tongue is closed and to be engaged therebeyond by any suitable instrumentality, the opening in the free end of the collar engaging in the angle formed by the closed end of the tongue, and means connected 15 with the front plate for retaining the tongue in closed position with the free end projecting outwardly therefrom.

3. A buckle suitable for application to dog collars or the like comprising a generally curved 20 body rectangular in cross-section to provide for sliding reception of the collar and having a front plate imperforate except for the provision of a tongue opening with side portions terminating in inturned but separated tabs to provide 25 a central slot for reception of a tongue, a tongue pivoted to the buckle behind the front plate and having an end portion forming a closed loop and disposed at an acute angle to the length of the tongue, the end portion being designed to 30 project through the tongue opening and cause the closed loop to project beyond the plate at the front of the buckle for engagement of a suitable instrumentality, the length of the tongue being received in the slot behind the inwardly 35 projecting tabs at the back of the buckle.

LEWIS H. MADER.
